UNITED STATES PATENT OFFICE.

GEORGES BAUJARD, OF PARIS, FRANCE.

CLOTH-PRESSING MACHINE.

1,070,318.

Specification of Letters Patent. Patented Aug. 12, 1913.

Application filed January 23, 1912. Serial No. 672,943.

To all whom it may concern:

Be it known that I, GEORGES BAUJARD, a citizen of the French Republic, residing at Paris, France, have invented certain new and useful Improvements in Cloth-Pressing Machines, of which the following is a specification.

Machines for pressing cloth are generally used by tailors and mainly serve for flattening the seams of suits after they have been made. There are known several constructions of such machines.

The machine according to this invention is characterized by a new arrangement of certain parts and mechanisms the most important of which is the mechanism which permits of rapidly bringing the smoothing iron down upon the cloth by means of a pedal and of producing at the end of the downward movement of the smoothing iron a pressure by means of a hydraulic device in order to obtain the desired effect. The lifting of the iron is also effected very rapidly owing to the counterweights and the cessation of the hydraulic pressure.

A machine according to this invention is shown by way of example in the accompanying drawings:

Figure 1 is a longitudinal vertical section. Fig. 2 is a plan view on the line A—B, Fig. 1 of the machine the upper part of the machine having been omitted. Fig. 3 is a front elevation of the machine. Figs. 4, 5 and 6 show the pressure lever and the transmission segment in various positions. Fig. 7 is an elevation of Fig. 5 seen from the right hand side. Fig. 8 shows on a larger scale in cross section the movable arm supporting the smoothing iron.

In the form of construction shown all the parts of the machine are mounted upon a frame composed of two uprights 1 and 2 connected by transverse bars 3 and 4. At the upper part of the frame a working table 5 is mounted. A jaw 6 for maintaining the cloth upon the table is pivotally mounted upon the frame. A supporting table 7 serves for carrying the parts of the cloth which are not to be worked upon, the vertical position of said table being adjustable by means of a device consisting of a rack and a pinion to be operated by hand by means of a handle 8. The smoothing iron 9 is held by means of a ball joint 10 at the end of a movable cylindric arm 11. The smoothing iron can be moved in any direction by means of its

handle 12. The movable arm 11 traverses two supports mounted at the end of a beam 17. One of these supports consists of a bearing surface 13 forming a slide and of a roller 14 which facilitates the displacement of the movable arm 11. The arm 11 is supported by the bearing surfaces 13—15 and the rollers 14—16. The rollers have an indentation at the middle so that their remaining surfaces are tangential with the surface of the tubular arm 11 at two points 38—39 only (Fig. 8). Owing to this arrangement the tubular arm 11 moves upon the rollers without slipping. The beam 17 is mounted at the end of a vertical standard 18 which is pivotally mounted in a suitable support 19 fixed upon a bracket 20. The vertical arm 18 has at its lower end an extension 19' formed by a rack with which engages a loose pinion 37 rigidly connected with a pinion 36 having two teeth. This rack is guided at its lower part in the transverse bar 4. It carries at its upper part a stud 21 upon which the end of a lever 22 is loosely mounted. At the other end of said lever 22 a counterweight 23 is arranged. Below the loose pinion 36 a segment 24 with two teeth is mounted which is rigidly connected with a pressure lever 25 and which is adapted to engage with the pinion 36 when the two teeth of this pinion are in front of the teeth of the segment. The other end of the pressure lever 25 is loosely secured to the rod 26 of a hydraulic press 27 mounted upon the frame. The lever 22 carrying the counterweight and which can pivot around the axle 28 is connected by a connecting rod 29 with a pedal lever 30 adapted to turn around a pivot 31 and carrying the counterweight 32 and a pedal 33. Below this lever a valve handle 34 is arranged which serves for operating the hydraulic press 27, this valve handle is held normally in lifted position. A finger 35 fixed upon the axle 28 serves for limiting the movement of the pressure lever 25.

The connecting of the sector 24 with the pinion 36 is shown in detail in Fig. 7, this sector having two teeth and is rigidly connected with the pressure lever 25, and opposite the same there is mounted the pinion 36 having two teeth and further a pinion 37 having a greater number of teeth and which stands opposite to the rack 19'. 110

The operation of the apparatus is as follows:—For lowering the smoothing iron the

pedal 33 has to be depressed. Through the intermediary of the connecting rod 29 and of the lever 22 with counterweight the rack 19' with its stud 21 and consequently the movable arm 11 and the smoothing iron are drawn along. At the same time the rack makes revolve the pinion 37 and with it the pinion 36 with two teeth, which thus is brought before the toothed sector with 10 which it engages as shown in Fig. 6 as soon as this sector is displaced. At the end of its stroke the pedal lever 30 operates the valve of the hydraulic press 27, and the pressure lever 25 is lifted. The two teeth of the segment 15 24 mesh with the teeth of the pinion 36 and through the intermediary of the pinion 37 they make the rack descend and produce the required pressure. To lift the smoothing iron the pedal is released, the counterweight 23 through the intermediary of its lever bringing the parts back to their normal position and permitting the valve handle to rise and release the pressure in the hydraulic press. Owing to this arrangement 20 there has been realized a machine for pressing cloth in which the lowering and lifting movements of the smoothing iron are effected rapidly; the hydraulic press enters into action only at the end of the descending movement.

The apparatus which forms the object of this invention cannot only be used for pressing cloth but it further can be used, for example, as a press for stamping, punching, 35 and the like, not only cloth but leather, wood, sheet metal and the like. This machine offers in all these cases the advantages accruing from its double movement, namely,

at the beginning of the operation a rapid movement then a consecutive pressing movement which permits of exerting a considerable pressure upon the object to be treated.

I claim:—

A cloth pressing machine comprising a 45 working table, a vertical standard carrying a smoothing iron, a rack forming the lower extension of said standard, a stud projecting from said standard, a counterweighted lever having a slot at the free end which engages 50 with said stud, a counterweighted pedal lever, a pull rod connecting said pedal lever with said lever of the standard to bring the iron toward the working table when said pedal lever is being depressed, a pinion engaging with said rack, a toothed segment connected with said pinion, a pressure lever for communicating final pressure to the smoothing iron, a toothed segment at the inner end of said 55 pressure lever adapted to mesh with said segment of the pinion, a hydraulic cylinder, a piston in said cylinder with which the end of the pressure lever is connected, and a valve for admitting fluid under said piston situated under said pedal lever so that it is opened only when the pedal lever has been depressed for a certain extent, substantially as described and for the purpose 60 set forth.

In witness whereof I have hereunto set my hand in the presence of two witnesses.

GEORGES BAUJARD.
